UNITED STATES PATENT OFFICE.

HOWARD M. BARBER, OF STONINGTON, CONNECTICUT, ASSIGNOR TO C. B. COTTRELL & SONS COMPANY, OF NEW YORK, N. Y., A CORPORATION OF NEW JERSEY.

INKING MECHANISM FOR BED-AND-CYLINDER PRINTING-PRESSES.

1,093,521.

Specification of Letters Patent. Patented Apr. 14, 1914.

Application filed June 30, 1911. Serial No. 636,204.

To all whom it may concern:

Be it known that I, HOWARD M. BARBER, a citizen of the United States, and resident of Stonington, in the county of New London and State of Connecticut, have invented a new and useful Improvement in Inking Mechanism for Bed-and-Cylinder Printing-Presses, of which the following is a specification.

10 The object of this present invention is to provide a novel inking mechanism for bed and cylinder printing presses in which the rollers are always driven in the same direction and in which a continuous and even 15 distribution of the ink on the form is obtained, the ink always being worked in one direction and the form rollers always being in contact with the vibrators during both the printing and return strokes of the 20 bed for insuring a thorough distribution of the ink on the form rollers, means being provided for raising and lowering the inking mechanism bodily without interfering with the connection between the several parts.

25 In the accompanying drawings, Figure 1 represents in side elevation so much of a bed and cylinder printing press as will give a clear understanding of the invention. Fig. 2 is a detail view showing the means for 30 vibrating the ink cylinder and vibrator rolls, Fig. 3 is a detail longitudinal vertical section through the inking mechanism and its raising and lowering means, Fig. 4 is a detail transverse vertical section showing 35 the means for raising and lowering the inking mechanism, and Fig. 5 is a detail section showing certain of the geared connections.

40 The sheet delivery mechanism and the mechanism for reciprocating the form bed are not shown herein as they form no part of the present invention and will not assist in a clear understanding thereof.

45 The reciprocating bed is denoted by 1 and the form thereon by 2; the impression cylinder by 3, the fountain roller by 4, the ductor roller by 5, the ink cylinder by 6, the distributing and carrying rollers by 7, 8, 9, 10, 11, 12; the vibrators by 13, 14, and the 50 form rollers by 15, 16, 17, 18.

The main drive shaft is indicated at 19, which shaft drives the cam shaft 26 through the gears 20, 21, 22, 23, 24, 25. The cams for controlling the movements of the fountain roller 4 and the ductor roller 5, are de-

noted by 27, 28 respectively, and their shaft by 29, which shaft is driven from the cam shaft 26 through the train of gears 25, 30, 31, 32, 33, 34.

The impression cylinder 3 is driven from 60 the drive shaft 19, through the gears 20, 21, 35, 36. The ink cylinder 6 is driven from the impression cylinder gear 36, through the gears 38, 39, 40, 41, and the vibrators 13, 14, are driven from the ink cylinder 65 gear 41, through the gears 42, 43 and 44, 45 respectively.

The vibrator rolls 13, 14, and the ink cylinder 6 may be vibrated by any desired means, such, for instance, as that shown in 70 the accompanying drawings, in which the shaft 6* of the ink cylinder 6 is reciprocated longitudinally by the worm 46 and worm wheel 47. The shafts 13* and 14* of the vibrator rolls 13, 14, are reciprocated 75 longitudinally by the rock levers 48, 49, from the ink cylinder shaft 6*.

The different parts of the inking mechanism are supported in a supplemental frame 50 hinged at 51 to the main frame to swing 80 vertically to move the form rollers 15, 16, 17, 18, into and out of engagement with the form 2. The means which I employ for raising the frame during the return stroke of the bed comprises a cam 52 fixed to the 85 shaft 26, which cam engages a roller 53 on an arm 54 of a rock lever pivoted at 55, said lever having preferably two arms 56 connected to the free end of the supplemental frame 50, by vertically arranged rods 57. 90 This cam 52 on the shaft 26 is so timed that the supplemental frame 50 will be lowered to bring its form rollers into contact with the form 2 during the forward printing stroke of the bed and will be raised to cause 95 the form rollers to clear the form during the return stroke of the bed.

It will be seen by the above construction that the form rollers are always driven in one direction by their contact with the vibrators, thus accomplishing the following results: first, the working of the ink in one direction; second, a continuous even distribution, and third, the ability of the machine to be successfully run at a higher rate 105 of speed because of the non-reversing movement of said rollers.

It is evident that various changes might be resorted to in the construction, form and arrangement of the several parts for accom- 110

plishing the results herein stated; hence I do not wish to limit myself to the construction herein set forth, but

What I claim is:

- 5 1. In a machine of the character described, a main frame, a supplemental frame hinged thereto, a reciprocating bed and its form carried by the main frame, an inking mechanism for the form carried by the supplemental frame, and rotary means having an uninterrupted driving connection with the inking mechanism arranged to automatically raise and lower the supplemental frame for bringing the inking mechanism out of and into contact with the form.
- 10 2. In a machine of the character described, a main frame, a supplemental frame hinged thereto, a reciprocating bed and its form carried by the main frame, an inking mechanism carried by the supplemental frame including an ink cylinder, a pair of vibrators driven continuously in one direction therefrom and a pair of form rollers driven continuously by each vibrator and rotary
- 15 20 25 means having an uninterrupted driving connection with the inking mechanism ar-

ranged to automatically raise and lower the supplemental frame for bringing the form rollers out of and into contact with the form.

3. In a machine of the character described, 30 a main frame, a supplemental frame hinged thereto, a reciprocating bed and its form carried by the main frame, an inking mechanism carried by the supplemental frame including an ink fountain, its roller, a ductor roller, an ink cylinder, distributing rollers, carrying rollers, vibrators, and form rollers, and rotary means having an uninterrupted driving connection with the several parts of the inking mechanism and arranged to raise and lower the supplemental frame for bringing the form rollers out of and into contact with the form.

In testimony, that I claim the foregoing as my invention, I have signed my name in 45 presence of two witnesses, this twenty eighth day of June, A. D. 1911.

HOWARD M. BARBER.
